CLAIM

The ornamental design for a golfers brush, as shown and described.

DESCRIPTION

FIG. 1 is a front elevational view of a golfers brush, showing our new design, the rear elevation being a mirror image thereof;

FIG. 2 is a top plan view thereof;

FIG. 3 is a bottom plan view thereof;

FIG. 4 is a left end elevational view thereof;

FIG. 5 is a right end elevational view thereof.

FIG 1

FIG 2
